Patented Aug. 15, 1922.

Henry Slaiger INVENTOR.

BY

Joseph A. Miller ATTORNEY.

UNITED STATES PATENT OFFICE.

HENRY SLAIGER, OF ATTLEBORO, MASSACHUSETTS, ASSIGNOR TO THE D. F. BRIGGS COMPANY, OF ATTLEBORO, MASSACHUSETTS.

POWDER CONTAINER.

1,425,909.

Specification of Letters Patent. Patented Aug. 15, 1922.

Application filed March 15, 1922. Serial No. 544,017.

To all whom it may concern:

Be it known that I, HENRY SLAIGER, a citizen of the United States, residing at Attleboro, in the county of Bristol and 5 State of Massachusetts, have invented new and useful Improvements in Powder Containers, of which the following is a specification.

This invention relates to certain new and 10 useful improvements in powder containers and pertains more particularly to a combined powder container and puff such as are commonly employed for toilet use.

The primary object of the invention is to 15 provide a container in which the closure therefor has a powder puff, which latter can be moved into and out of the closure, so as to be housed within the closure when the latter is in container-closing position 20 and to be projected to lie without the closure when the closure is removed from the container and the puff is to be used as such.

A further object of the invention is to 25 provide a container of this type in which novel means is employed for attaching the puff to the closure, which means also functions to effect movement of the puff into and out of the sleeve, and to assist in holding the closure in container-closing position on 30 the container, and may still further be employed to assist in removing the closure from the container, serving as finger grips in the performance of the last mentioned function.

35 The invention still further aims to generally improve and simplify and reduce the cost of production of articles of this type and has still further and other objects which will be later set forth and manifested in the 40 course of the following description.

In the drawings:

Figure 1 is a side elevation of the invention, the parts being in closed position of the container;

45 Figure 2 is a section on line 2—2 of Figure 1;

Figure 3 is a section on line 3—3 of Figure 1; and

50 Figure 4 is a detail side elevation of the closure in removed position ready for use with the puff projected.

In proceeding in accordance with the present invention, a preferably cylindrical container 1 is employed, which has a suitably closed bottom end 2, and may have an

attaching bail 3; for securing the container to a chain or otherwise connecting same.

The closure consists of an outer sleeve 3, which is formed to closely fit within the interior of the container and has an end wall 4, formed with a rim 5, which latter is formed to closely fit about the exterior of the container. The sleeve 3, has a pair of longitudinal diametrically opposed slots 6, and slidably fitted within the sleeve 3, is a collar or interior sleeve 7, which forms a ferrule for the puff 8. The puff 8, may be provided with an attaching loop 9, through which a securing pin 10, passes, the puff extending at its inner end within the ferrule 7, while the pin extends through opposite sides of the collar through apertures or holes provided therefor, and has its ends extending through the respective slots 6, and headed at 11.

When the closure is in container-closing position, the puff 8 occupies the position of Figure 2, in which the ferrule 7 and the puff are disposed within the sleeve 3, the ends of the pin 10 being received in slots 12 provided therefor in the container 1, the slots 12 being open at their outer ends as shown in Figures 1 and 2. Preferably the ends of the pin have a snug fit with the walls defining the slots 12 so that the pin 85 assists in holding the closure onto the container. When the puff is to be used, the closure is removed, which may be effected by grasping the heads 11 of the pin with the fingers, and the pin then moved lengthwise of the slot 6 so as to project the ferrule and the puff without the sleeve 3, as depicted in Figure 4. After use of the puff, the pin 10 is again slid in the slot 6 to move the ferrule and puff to lie within the sleeve 3, 95 whereupon the closure is repositioned on the container.

From the foregoing it will be apparent that the pin 10 acts to not only secure the puff to the sleeve or ferrule 7, but also acts 100 to allow the puff and ferrule to be moved into and out of the sleeve 3, in addition to affording means for securing the closure to the container and for providing finger grips to enable removal of the closure.

Having thus described my invention, what I claim as new and desire to secure by Letters Patent is:

1. In a powder container, a container body having a closed end and having op- 110

- posed slots extending through its opposite end, a closure for the container body having an outer sleeve fitting within the container body and having a rim fitted over the outside of the body, a ferrule within the sleeve, a puff having a loop in the ferrule, and a pin having headed ends, the pin being receivable in the slots of the body and extending through the loop and through the ferrule and through the slots of the outer sleeve, whereby upon removal of the closure the pin may be moved through the slots of the outer sleeve to project the puff beyond the outer sleeve.
2. In a powder container, a container body, a closure therefor having an outer sleeve formed with opposed slots, a ferrule slideable in the sleeve, a puff in the ferrule, a pin extending through the ferrule and operating in the slots of the sleeve and means connecting the puff to the pin, so as to move the puff into and out of the sleeve upon movement of the pin.
3. In a powder container, a container body, a closure for the body having a sleeve slideable within the body, a powder puff having a ferrule slideable in the sleeve, and combined means to connect the puff to the ferrule and for effecting the sliding movements of the latter within the sleeve.
4. In a powder container, a container body having opposed longitudinal slots, a closure for the body having a sleeve fitting

within the body and having a rim fitting over the exterior of the body, a ferrule within the sleeve, a pin extending through the ferrule and through the slots of the body, a puff in the ferrule, and means to connect the puff to the pin whereby to cause the ferrule and therewith the puff to move into and out of the sleeve upon sliding of the pin.

5. In a powder container, a container body, a closure therefor having a sleeve engageable with the body, a puff receivable in the body, a ferrule carrying the puff and slideable in the sleeve, and means to effect movement at will of the ferrule and puff into and out of the sleeve.

6. In a powder container, a container body, a closure therefor having a sleeve engageable with the body, a puff receivable in the body, a ferrule carrying the puff and slideable in the sleeve, means secured to the ferrule to effect movement at will of the ferrule and puff into and out of the sleeve, and means to removably connect the first named means to the body.

In testimony whereof I have signed my name to this specification in the presence of two subscribing witnesses.

HENRY SLAIGER.
